UNITED STATES PATENT OFFICE.

JOHN M. AHLGREN, OF INDIANAPOLIS, INDIANA, ASSIGNOR TO AHLBELL BATTERY CONTAINER CORPORATION, OF WAUKEGAN, ILLINOIS, A CORPORATION OF ILLINOIS.

ART OF MANUFACTURING CONTAINERS.

Original application filed April 28, 1922, Serial No. 557,131. Divided and this application filed March 24, 1923. Serial No. 627,425.

My invention relates more particularly, though not exclusively, to the manufacture of battery containers commonly of a form and construction to receive the battery elements of a plural cell battery as, for example and more particularly, storage batteries such as are used in automobiles and which containers are, by preference, formed of any suitable rubber compound; the present application being a division of my application for United States Letters Patent, upon which Letters Patent No. 1,485,061 were granted February 26, 1924.

My objects are to reduce the cost of manufacture of such containers and more especially containers of the type wherein the bottom, side walls and partitions dividing the container into cells are integral with each other; to improve upon containers as hitherto provided; to produce a highly satisfactory and durable construction thereof; and other objects as will be manifest from the following description.

Referring to the accompanying drawings: Figure 1 is a perspective view, with the parts disassembled but in relatively alining position, of a core-equipped vulcanizing mold structure suitable for practicing my improved process. Figure 2 is a similar view of the various elements from which the container may be formed in the mold shown in Fig. 1. Figure 3 is a perspective view of the completed container, with portions thereof broken away to disclose interior details. Figure 4 is a plan view of the bottom, core-equipped, plate of the mold, one of the sections of the core being shown in section. Figure 5 is a broken, vertical, sectional view taken through the mold and showing the parts illustrated in Fig. 1, in assembled position, but with the container-forming elements omitted, the section being taken at the line 5 on Fig. 4 and viewed in the direction of the arrow. Figure 6 is a vertical sectional view of the structure shown in Fig. 4, this section being taken at the line 6 on Fig. 4 and viewed in the direction of the arrow. Figure 7 is a view like Fig. 6 of the upper right-hand corner of the structure shown in this figure, this view showing the adjacent portion of the container formed therein and illustrating the position occupied by the excess container-forming material in the molding of the material to form

the container. Figure 8 is a view in side elevation of the plate to which the cores are connected, but with the cores omitted, one-half of the view being in section with the core plate for the handle at this end of the mold omitted; and Figure 9, a perspective view of the core plate for the handle portion of the container.

In practicing my improved process in the production of plural-cell battery containers, as, for example, for storage battery purposes, I preferably form the container from elements of any suitable rubber compound capable of resisting the action of the acid used in storage batteries and vulcanizable into the desired hard condition, such rubber compounds being commonly known in the art. The elements referred to, and as shown more particularly in Fig. 2 and preferably employed, comprise the opposite side-wall-forming sheets 11, the end-wall-and-handle-forming sheets shown as each formed of the plane section 12, and the apertured sheet-section 13, the partition-forming sheets 14 and 15, the bottom-forming sheet 16, and the rib-forming strips 17. The various elements illustrated in Fig. 2 are shown in inverted condition, compared with the position they occupy in the finished container illustrated in Fig. 3, as the container is illustrated in the drawings as being molded in inverted condition. The edges of the sheets 14 and 15, shown uppermost in Fig. 2, contain series of notches 18, the walls of which converge downwardly, to receive the rib-forming elements 17, the side walls of which converge downwardly, the elements 17 extending crosswise of the sheets 12, 14 and 15 and abutting at their ends the inner faces of the sheets 12. The edges of the elements 13 shown lowermost in Fig. 2, are provided with depending portions 19 which, in the finished structure, extend above the plane of the upper edges of the side walls 11 and the partitions 14 and 15, and are outwardly offset from the walls 12, the portions 19 containing openings 20 therein to form finger grips by means of which the finished battery may be conveniently handled.

As a preface to the following description it may be stated that the various container-forming elements shown in Fig. 2 are assembled in a mold, wherein they are subjected to pressure and vulcanizing heat,

all as hereinafter fully explained, for the purpose of uniting the various elements at the portions thereof which extend contiguous to each other to form the finished integral vulcanized container shown in Fig. 3. The construction of mold illustrated and which is of a very desirable form for use in the practicing of my improved method comprises a bottom plate 21 from which 10 rises, centrally thereof, the core-structure about which the elements shown in Fig. 2 are molded. The core-structure shown, and suitable for molding a 3-cell container, is formed of three similar sections 22 extending 15 cross wise of the plate 21 and extending at their lower ends into recesses 23 extending transversely of the upper, relatively narrow, portion 24 of the plate 21, these core-sections being thus spaced apart as 20 represented at 25. The core sections 22 are secured to the plate as by the bolts 26 and are preferably of the same length as the recesses into which they extend. The opposite walls of the sections 22 converge 25 slightly in an upward direction in Fig. 1 for the purpose of providing draft and the spaces 25 are provided to receive the elements 14 and 15. The upper surfaces of the sections 22 in Fig. 1 contain series of alining notches 27 the opposite walls of which converge downwardly, for receiving those portions of the elements 17, which, in the assembled position of the elements shown in Fig. 2, extend between the elements 14 30 and 15 and between these elements and the elements 12. By locating the core elements 22 as stated, the plate portion 21 extends laterally in all directions beyond these core sections and in a plane below the latter, 35 thereby affording the continuous ledge 28 surrounding the group of core-sections 22. The plate 21 at opposite edges thereof adjacent the narrow ends of the core-sections 22 is provided with bars 29 which rest upon certain portions of the ledge 28 and are secured, as by screws 30, in position to overlap the lower edges of the ends of the core-sections 22 and aid in preventing displacement of the latter. The portions of the 40 ledge 28 at the ends of the plate 21 are recessed, as represented at 31, to receive core-plates 32 hereinafter described, and beyond these recesses are recessed at 33 for a purpose hereinafter described. The core-plates 45 32, shown as recessed as represented at 34, at their outer ends, to interfit with the ends of the bars 29 vertically slidingly fit within the recesses 31 and between their ends present the laterally-opening channels 35 of general U-shape which open at their ends through the upper surfaces of the core-plates 32 and in which the handle-portions 50 of the container are formed, the recesses 33 having curved lower surfaces substantially concentric with the lower surfaces of

the channels 35 but in a lower plane as shown.

The ledges provided by the upper surfaces of the bars 29 and the surfaces provided by the tops of the core-plates 32 constitute the bottom surfaces of the mold cavity, for the portions of the container located between the handle portions thereof, and the channels constitute the mold cavities for the handle-portions. The ledges 28 serve 75 as supports for the side and end walls hereinafter referred to, of the mold.

In the use of the mold structure for producing a container, the container-forming material located in the mold is subjected to vulcanizing heat, as hereinbefore stated, and to this end the core sections 22 of the mold structure, which latter is preferably made of metal, are chambered, as represented at 36, to receive the medium, as, for example, steam, for effecting the vulcanizing operation. In the arrangement shown the bottom plate 21 of the mold contains a plurality of passages 37 and 38 opening into the respective chambers 36 and serving as a means for circulating steam through these chambers.

The side-and-end-wall-forming portion of the mold is represented at 39, it being shown as a hollow rectangular structure open at its top and bottom and adapted to be applied to seating position at its lower edges upon the ledge 28 to encircle the core-structure formed of the sections 22 and provide, between this core-structure and the structure 39, a continuous space which is occupied by the container-forming elements 11 and 12 and portions of the elements 13 in the assembly of the parts, the wall-forming portion 39 of the mold relatively closely fitting the vertical exterior surfaces of the bars 29 and the core-plates 32. The edges of the end-wall-forming portions of the structure 39 shown as lowermost in Fig. 1, are provided with depending portions 40 which, in the assembly of the structure 39 with the core-equipped lower plate 21, extend into, and conformingly fit, the recesses 33. The inner surfaces of the wall portions of the member 39 extending adjacent to the core-plates 32 are recessed at their lower edge portions, as represented at 39^a to provide for the molding of a sufficient body of the container-forming material at the juncture of the handle-portions of the container with 100 the walls carrying them.

The mold-member 39 extends above the top surfaces of the core sections 22, and contains dowel-receiving openings 41 to receive the depending dowels 42 provided on the top plate 43 of the mold. This plate is provided with a depending rectangular portion 44 inset from the marginal edges of the plate 43 throughout their extent and of such shape and proportions that it extends into the up- 105 110 115 120 125

per end of the opening in the structure 39, but in spaced relation thereto throughout its extent, to provide the continuous clearance represented at 45, the parts being so proportioned and arranged that a space is provided between the upper surfaces of the core sections 22 and the under surface of the depending portion 44 of the plate 43 in which space the bottom-forming sheet 16 of the 10 container is located in the molding process.

In forming the container, the various elements shown in Fig. 2 are heated before being applied to the mold, to render the rubber compound of putty-like consistency, the 15 partitions 14 and 15, being then inserted into the spaces 25 to rest at their lower edges on the portion of the plate 21 beneath them, the notches 18 registering with the notches 27 in this position of the sheets 14 and 15 and 20 the elements 17 then introduced into the notches 18 and 27; the elements 13 are then applied to the core-plates 32 to cause the portions 19 to extend into the channels 35 and the assembled core-plates 32 and elements 25 13 applied to position on the core-plate 21, the plates 32 being positioned as shown in Fig. 1; the sheets 12 are then applied to the outer end surfaces of the two outermost core sections 22 to extend at their lower edges 30 upon the tops of the core-plates 32 and into the spaces between the core-sections 22 and the elements 13; the sheets 11 are then applied to the opposed remaining sides of the core-structure to rest upon the bars 29, and 35 preferably completely overlap the end edges of the sheets 12; and the sheet 16 then applied to the upper edges of the other elements applied to the core-structure as stated, the sheet 16 being of such dimensions that it 40 will, by preference, extend substantially flush with the outer surfaces of the elements 11 and 12.

The mold structure 39 is then applied to the plate 21 to surround the container-forming elements applied to the core-structure as stated, the structure 39 seating at its lower edge upon the ledge 28 and its depending portions 40 extending into the recesses 33. The top plate 42 is then applied to the top 50 of the structure 39.

It may be here stated that the amount of container-forming material introduced into the mold, or in other words the amount of this material forming the elements shown in 55 Fig. 2, is sufficiently in excess of the amount of the material contained in the finished container, this excess being preferably provided in the upper sheet 16, that the container-forming material, when subjected to the 60 operations hereinafter described, will be caused to completely fill the mold cavities provided and permit of the material being subjected to the desired compressive stresses.

In accordance with the preferred manner 65 of practicing my invention, the contents of

the mold, in plastic condition as stated, are subjected to relatively great pressure by any suitable means for the purpose of forcing the top plate 43 with great force toward the bottom plate 21, it being preferred that a 70 force of substantially three-fourths of a ton per square inch be applied, with the result that the container-forming plastic material is forced with great pressure into all portions of the mold cavities, thereby firmly bonding 75 contiguous marginal, and edge, portions of the various elements shown in Fig. 2. The mold is then placed in a hydraulic vulcanizer which, by preference, exerts the same force as that above stated against the top 80 plate 43 and the plate 21, the steam in the vulcanizer circulating through the chambers 36 in the core-sections 22, by reason of the provision of the passages 37 and 38, the mold remaining in the vulcanizer until the 85 container-forming material has become vulcanized to the desired degree, in which operations above stated, the various elements of Fig. 2 are caused to become united at their contiguous marginal portions and edges, 90 into a substantially homogeneous structure and vulcanized to produce the integral container shown in Fig. 3.

After the mold and its contents have been subjected to the vulcanizing heat for the 95 desired length of time the mold and its contents are preferably cooled, as for example by filling the hydraulic vulcanizer with cooling water, in place of the steam, and the mold and its contents cooled off while maintaining the pressure stated, against the mold-plates.

In the subjection of the contents of the mold to the high pressure as stated, the excess material is forced upwardly into and 100 through the clearance 45 and into the substantially horizontal space between the upper edges of the structure 39 and the under side of the plate 43 at its marginal portions, as represented more clearly in Fig. 7.

After cooling the formed container it is 105 removed from the mold preferably by first removing the top-plate 43 following which the fin formed of the excess material referred to and represented at 46 is preferably removed as, for example, by running a knife around the lower edge of this fin where it connects with the main portion of the molded container. The mold is then supported at the portion 39 thereof in any 110 suitable manner at opposite sides of this portion, as at the parts thereof which project laterally beyond the core-plate 21 (Figs. 5 and 6) and downward force applied to the bottom portion of the formed container, as 115 through the medium of a presser-head (not shown) which operates through the upper open end of the wall-forming portion 39, for separating the core-member and container, as a unit, from the portion 39, the op- 120 125 130

posed inner side-walls of which the latter preferably converge slightly upwardly. The bond between the container and the wall structure having thus been broken, the 5 formed container and core-member as a unit, and the portion 39, may be fully separated, which leaves the formed container free to be stripped from the core-equipped plate 21 which may be readily effected in 10 any suitable way, as for example, by first removing the bars 29 and then forcing the container from the core-structure 21-22. After the container has been stripped from the core-structure 21-22, the core-plates 32 15 are removed from the handle-portion of the container.

A container constructed in accordance with my invention is not only highly durable, economical of manufacture, and leak- 20 proof, but also presents a neat and attractive appearance.

The feature of so forming the mold that the fins of excess material where they join the body of the container, extend in line 25 with the outer surfaces of the container, instead of in line with the top surface of the container considering it in inverted condi-

tion, is of advantage, as thereby the molded structure is free of lateral projections at the body portion of the container which, if existent, would obstruct the ready removal of the portion 36 of the mold from the form container. 20

While I have illustrated and described a particular construction of apparatus for use in carrying out my improved method, I do not wish to be understood as intending to limit my invention thereto, as the same may be practiced by employing other apparatus, and variations in the method as described 40 may be practiced without departing from the spirit of my invention.

What I claim new, and desire to secure by Letters Patent, is:

The method of manufacturing receptacles, 45 which consists in heating the vulcanizable material from which the receptacle is to be formed, positioning the material in heated condition in a mold, subjecting the heated material, in relatively soft condition, to 50 pressure to fill the mold cavity, and thereafter vulcanizing the material.

JOHN M. AHLGREN.
